UNITED STATES PATENT OFFICE.

LEE S. CHADWICK, OF CLEVELAND, OHIO.

DESIGN FOR A STOVE.

45,223.

Specification for Design.

Patented Feb. 10, 1914.

Application filed December 6, 1913. Serial No. 805,167. Term of patent 14 years.

To all whom it may concern:

Be it known that I, LEE S. CHADWICK, a citizen of the United States, residing at Cleveland, in the county of Cuyahoga and State of Ohio, have invented a new, original, and ornamental Design for Stoves, of which the following is a specification, reference being had to the accompanying drawing, forming part hereof, wherein—

Figure 1 represents a front elevation and

Fig. 2 an end elevation of the stove exhibiting my new design.

I claim:

The ornamental design for a stove as shown.

LEE S. CHADWICK.
